UNITED STATES PATENT OFFICE.

BRADFORD SHERMAN SHAW, OF LAURINBURG, ASSIGNOR OF ONE-HALF TO
W. R. BARKSDALE, OF WILMINGTON, NORTH CAROLINA.

SEAL-LOCK.

SPECIFICATION forming part of Letters Patent No. 536,585, dated March 26, 1895.

Application filed April 8, 1893. Serial No. 469,615. (Model.)

To all whom it may concern:

Be it known that I, BRADFORD SHERMAN SHAW, a citizen of the United States, residing at Laurinburg, in the county of Richmond 5 and State of North Carolina, have invented a new and useful Improvement in Seal-Locks, of which the following is a specification.

The invention relates to seal locks of the kind commonly used on freight car doors, and 10 is intended to provide a simple and cheaper seal lock, and one giving a greater guaranty of proper operation.

Figure I, shows the lock (except the hasp, which is shown in Fig. V) with the lock bolt, 15 R, and its bearings, f, and d, the staple, e, and the seal frame, o, p, q, r. Fig. II, shows the lock bolt alone with its ring, a, its notch, b, and its knife, c. Fig. III, shows the end 20 of the seal lock as it appears if looking at the upper end of Fig. I. Fig. IV, shows a longitudinal section of the seal-lock with the lock bolt R, in the position it has when locked. Fig. V, shows the lock as it appears when on 25 the car door, except that it has here a horizontal instead of a vertical position, and shows the hasp locked under the lock bolt.

The same letters refer to the same parts throughout.

The entire lock frame Fig. I, including the 30 bearings, f, and d, and the staple, e, are of one piece of metal. The lock bolt R, Fig. II, has in one end a ring, a, on its side a notch, b, with the shoulder of the notch toward the ring right angled, and in the other end from the ring, a, projecting piece of metal, sharp or blunt, which 35 acts as a defacer of the seal. The notch, b, and the knife, c, are on opposite sides of the rod. The knife c is so placed that when the bolt R is at its uppermost limit, the knife will 40 just clear the upper side of the seal frame o, p, q, r.

The frame of the lock, n, n, n, Fig. I, has at one end an elevated portion, d, forming a bearing for the lock bolt, R, at the other end 45 another bearing, f, and between these two bearings the staple, e, over which fits the hasp, H, Fig. V. The journal box in the bearing, d, is made the exact size of the lock-bolt, R, so that the latter is prevented by the ring, a, 50 at one end and the knife, c, at the other from sliding entirely out of the journal box. The

ring a, is so made as to be easily removed from the lock bolt.

In the journal-box k, along that side of the said journal-box nearest to the seal frame, o, 55 p, q, r, is a groove, h, which runs longitudinally with said journal-box, k, and opens into the face of the seal frame along the line indicated by the letters s, t, Fig. I, and along a line in the side of said journal-box k, which 60 line shall run longitudinally with the journal box k, and parallel with the direction of groove h is another groove, i, which does not extend of to the outer face the bearing f. The groove, i, is represented in my drawings as lying at 65 an angle of ninety degrees around the journal box, k, from the groove h, but it may lie at any convenient angle. These grooves, i and h are made of a suitable size and shape to admit of the passage of the knife, c, through 70 them as the bolt, R, is pushed in or out of the journal box, k. Extending around the journal-box, k, at the end shown in Fig. III, is a flange, m, (seen better in Fig. V) which is 75 cut away between, i and h.

The outer face of the bearing, f, is enlarged so as to form the frame o, p, q, r, Fig. I. For holding the seal in the upper edge of this frame is an opening wide enough to admit easily the card seal. This seal may be of card 80 board, of thin metal, or of both, and is made of sufficient length to extend when in position above the seal frame and above the point of highest elevation to which the knife c may be carried, as pointed out above. In the rear 85 part of the bearing, f, as shown in Fig. IV is a recess into which are fitted a metal gravity catch, A, and a flat spring, B. The recess opens into the journal-box, k, at, l, and the point of the gravity catch, A, projects through 90 this opening into the journal-box as shown in Fig. I, but may be pressed back flush with the side of the journal-box. The flat spring, B, is screwed firmly by its upper end to the lock frame, and its lower end is curved at, x, to 95 afford a support for the gravity catch. The catch is so arranged that there is no play in the recess and any force exerted upward (and that is the only direction any force can be exerted) on it falls on the upper shoulder of 100 the lock frame instead of on the spring, B. The spring B, and catch, A, are both protected

from improper interference by being entirely covered by the lock frame when the latter is in position, as may be seen from Fig. V.

My lock is attached to the car, or car-door, 5 by bolts extending through to the interior of the car, and there secured by nuts. The heads of these bolts are let in flush with the outer edge of the lock frame, and one of them is placed underneath the lock bolt, R. These 10 precautions are taken to provide against intermeddling by removing the lock.

Having described my invention, I will now describe its operation.

The seal card is first introduced through 15 the aperture in the upper part of the frame, o, p, q, r, leaving a portion of the card extending above the frame. The bolt, R, is inserted in the bearing, d, the ring, a, having been first removed, and then the ring is replaced. While 20 the bolt is in the position shown in Fig. I, the hasp, H, is placed over the staple, e. The bolt is then pushed forward until the knife, c, reaches the bearing, f, the end of the bolt having entered the journal-box, k. The bolt is 25 then revolved to the left until the knife, c, comes opposite to the groove, i. The bolt is then pushed forward through the journal-box, k, the knife passing through the groove, z, until the knife clears the groove, i, at the opposite end from which it entered. The bolt 30 is then revolved to the right through an angle of ninety degrees, the knife passing along the space where the flange, m, is removed as shown in Fig. III. The knife after this rotary movement being then opposite the groove, h, at 35 its upper end, the bolt is drawn down, whereby the knife, c, enters the groove, h. When the bolt is being revolved, before being drawn downward the knife, c, impinges against that 40 portion of the seal card that extends above the frame, o, p, q, r, as pointed out above, and as soon as the bolt is drawn downward the knife immediately cuts into the seal card, leaving however, the upper portion of the seal

card uncut. This uncut portion of the seal 45 card holds together the severed portions of the card. When the knife, c, is in position to pass through the groove, h, the notch, b, is at the rear part of the rod, and so placed that the moment the knife in its downward movement becomes hid underneath the frame, o, p, q, r, the notch, b, is caught by the gravity catch, A. The lock is then secure, the catch, A, rendering it impossible to push the bolt upward or backward and any downward movement of the rod resulting in severing the seal card.

The security of my lock is rendered much greater by providing for the use, in connection with my lock, of the ordinary wire and 60 lead seal lock. This is done in this manner, namely: Through the bearing, d, is a small hole, shown in model, and through the lock bolt, R, is another hole of same size, these 65 holes being so situated that they come in line one with the other at the moment the lock bolt, R, is caught by the catch, A, in notch, b. The usual wire may then be introduced through these holes and sealed with the usual lead seal. This makes the lock twice locked, 70 once by the catch, A, and once by the wire and lead seal just mentioned.

What I claim is—

In a seal lock, in combination, the lock frame, the seal frame, the lock bolt having a notch 75 b, and a knife c, the lock frame holding a tumbler catch adapted to engage the notch b in the bolt, and a flat spring having a curved end adapted to support the tumbler catch, and the journal-box having a flange m, and 80 slots i, and h, the latter opening in the face of the seal frame, and a seal card, substantially as set forth.

April 7, 1893.

BRADFORD SHERMAN SHAW.
